UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

VEHICLE-FRAME.

1,192,114.

Specification of Letters Patent. Patented July 25, 1916.

Application filed December 8, 1914. Serial No. 876,098.

To all whom it may concern:

Be it known that I, ALDEN L. PUTNAM, a citizen of the United States of America, residing at Detroit, in the county of Wayne and State of Michigan, have invented certain new and useful Improvements in Vehicle-Frames, of which the following is a specification, reference being had therein to the accompanying drawings.

- 10 The invention relates to vehicle frames and has more particular reference to the construction of the horn for attaching the end of the sill to the spring and the manner of securing said horn to the sill. In the 15 present state of the art it is usual to form the sills of the frame of metallic channel bars tapering toward their ends and to form the horn, arranged at the end, of a separate casting or forging. The two parts are 20 secured by riveting the shank of the horn to the web of the channel, and further by securing the flanges of the channel by a riveted pin extending through the shank of the horn. This latter attachment is 25 objectionable, first, because the riveted ends interfere with the smooth finish of the sill and further because the boring of the flanges in the horn for the pin increases the cost of construction.
- 30 With the present invention I have obtained a better joint and a surer fastening between the sill and the horn, and one avoiding the necessity of a riveted pin, the invention comprising the construction as 35 hereinafter set forth.

In the drawings: Figure 1 is a side elevation of the end portion of the sill showing the horn attached thereto; Fig. 2 is a plan view; Fig. 3 is a section on line 3—3 40 Fig. 1, and Fig. 4 is a section on line 4—4; and Fig. 5 is a plan view of the blank from which the sill is formed.

A is the sill of any suitable form, but as shown provided with curved tapering end 45 portions of channel-shaped cross section. B is the horn for attachment to the springs (not shown), and which also is of any suitable construction. As shown, the horn B is provided with a stepped shank portion C, 50 which is riveted or spot-welded at D to the web portion of the sill.

To secure the flanges of the channel to the horn and to avoid the necessity of rivet-

ing, the blank from which the sill is pressed is formed with projecting ears E on opposite sides thereof. These ears may be readily formed from portions of the stock which would otherwise be wasted, so that there is no increase in stock. After the insertion of the shank of the horn in the channel these 60 ears E are bent over so that their edges abut against each other, as shown in Fig. 4. The shank C is also provided with a stepped portion F, which forms a filler against which the inner faces of the ears E bear. 65 To complete the securing the abutting edges of the ears are welded together and the joint between the end edges of the sill and abutting shoulder on the horn are also preferably welded, as indicated at G. 70

The construction above described is one which can be formed more cheaply than the constructions heretofore used, and inasmuch as the sheet metal forms a closed ring about the cross-section of the horn an 75 additional element of strength is provided. Furthermore the construction is one which provides a smooth surface free from rivets readily finished to a smooth contour.

What I claim as my invention is:—

1. In a vehicle frame, the combination with a channel sill having a tapering end portion, of a horn provided with a flaring shank fitting the channel of said sill, ears integral with the flanges of said sill bent to 85 overlap said shank and to abut against each other, the ends of said ears also abutting against a shoulder on the shank, and said abutting edges being welded to each other.

2. In a vehicle frame, the combination 90 with a sill of channel section having a tapering end portion, of a horn provided with a flaring shank fitting the channel and provided also with a shoulder bearing against the end of the sill, and integral ears projecting from the flanges of said channel and bent to overlap said shank, the joint between the edges of said ears and that between the end of the sill and the abutting shoulder on the horn being welded. 95

In testimony whereof I affix my signature in presence of two witnesses.

ALDEN L. PUTNAM.
